UNITED STATES PATENT OFFICE.

ARCHER A. BULL, OF DAHOGA, PENNSYLVANIA.

BOMB.

1,301,098.

Specification of Letters Patent. Patented Apr. 22, 1919.

Application filed November 12, 1918. Serial No. 262,215.

To all whom it may concern:

Be it known that I, ARCHER A. BULL, a citizen of the United States, residing at Dahoga, in the county of Elk and State of Pennsylvania, have invented certain new and useful Improvements in Bombs, of which the following is a specification.

The invention has relation to devices for use in warfare, the purpose being to direct the discharge outwardly in an approximately horizontal direction rather than upwardly or downwardly, with the result that a greater destruction is effected for an equal amount of explosive and material to be scattered such as shrapnel.

The invention has relation to bombs designed to be dropped from aircraft, the purpose being to impart a rotary movement to the bomb and to insure horizontal delivery of the missiles to be projected.

The drawing illustrates a preferred embodiment of the invention, however, it is to be understood that in adapting the same to meet different conditions, various changes in the form, proportion, and minor details of construction may be resorted to without departing from the nature of the invention as claimed hereinafter.

Referring to the drawing hereto attached. Figure 1 is a view in elevation of a bomb embodying the invention.

Fig. 2 is a top plan view, a portion being broken away and in horizontal section on the line of 2-2 of Fig. 1.

Fig. 3 is a vertical central section on the line 3-3 of Fig. 2, the propeller and the upper portion of its stem being omitted and an intermediate portion of the firing pin being broken away.

Corresponding and like parts are referred to in the following description and indicated in the several views of the drawing by like reference characters.

The bomb comprises a body portion 1 in which is formed a plurality of openings 2 having a radial arrangement. A vertical opening 3 is formed centrally of the body 1 and intersects the inner ends of the radial openings 2 and is in communication therewith. The opening 3 extends from the lower side of the body 1 to within a short distance of the top thereof. Any number of radial openings 2 may be formed in the body of the bomb and the body comprises radially protuberant portions 4 corresponding in number with the number of radial openings 2. The

radial openings 2 are adapted to receive the charge such as an explosive and shrapnel or other form of missiles to be projected. Caps 5 close the outer ends of the openings 2 and 60 may be secured to the body in any preferred way. As shown the caps 5 are of concavo-convex form and threaded into enlargements of the outer ends of the radial openings 2. A plug 6 is fitted in the opening 3 and is retained in place therein in any manner. As shown the plug 6 is held in the opening 3 by a screw-thread joint 7. Recesses 8 are formed in the sides of the plug 6 opposite the inner ends of the respective radial openings 2. Openings 9 connect the lower ends of the recesses 8 with a longitudinal opening 10 formed centrally within the lower portion of the plug 6. Fulminate or other charge igniting composition 11 is located at 75 the inner end of the opening 10. A firing pin 12 is disposed to operate in the opening 10. A portion of the firing pin is reduced, as indicated at 13, and this reduced portion receives a washer 14 or like form of retainer 80 by means of which the firing pin is held in place. The reduced portion 13 is of such a length as to admit of the firing pin having ample movement to explode the fulminate 11 and fire the bomb. The outer end of the 85 opening 10 is enlarged and receives an expansible helical spring 15 which normally holds the firing pin projected.

One of the features of the invention is to impart a rotary movement to the bomb 90 when in flight and for this purpose a propeller 16 is provided and as shown a stem 17 connects the propeller 16 with the body of the bomb. The propeller 16 may be of any design or structure so long as it serves 95 to impart a rotary movement to the bomb while the latter is in flight.

A bomb constructed in accordance with the present invention is adapted to contain charges of any nature. When the bomb is 100 released it assumes a position with the firing pin 12 disposed vertically and the radial openings 2 in horizontal arrangement, this position being assured by means of the propeller which at the same time imparts a 105 rotary movement to the bomb. When the bomb strikes an object the firing pin 12 is driven upwardly into the plug 6 thereby setting off the fulminate 11 and firing the bomb which discharges horizontally thereby causing 110 the greatest damage to a hostile body or territory.

The foregoing description and the drawings have reference to what may be considered the preferred, or approved, form of my invention. It is to be understood that I 5 may make such changes in construction and arrangement and combination of parts, materials, dimensions, et cetera, as may prove expedient and fall within the scope of the appended claims.

10 Having thus fully described my invention, what I claim as new and desire to secure by Letters Patent is:—

15 1. A bomb, comprising a body having a vertical opening and radial openings, the latter containing charges, a plug held in the vertical opening and having its side recessed in line with the radial openings, said plug having a centrally disposed longitudinal opening and other openings leading from 20 the longitudinal openings into the said re-

cesses and a firing pin held within the longitudinal openings of the plug.

2. A bomb, comprising a body having a central vertical opening and lateral openings radiating from the central opening, a 25 plug secured in the central opening and closing the inner ends of the lateral openings and having a longitudinal opening and branch openings leading therefrom and into the lateral openings, a firing pin in the longitudinal opening of the plug, charges in said lateral openings and caps closing the outer ends of the lateral openings. 30

In testimony whereof I affix my signature in presence of two witnesses.

ARCHER A. BULL.

Witnesses:

A. P. HUEY,
WILLIAM BRIMMER.
